UNITED STATES PATENT OFFICE

2,092,483

HOG BEATER PADDLE

Hobart H. Todd, Oak Park, Ill.

Application June 22, 1936, Serial No. 86,541

4 Claims. (Cl. 17—18)

The invention relates to improvements in hog beater or scraper paddles and has for its primary object the provision of an improved beater paddle of the character indicated which is so constructed and arranged as to prolong the time during which the same may be effectively used.

Other objects will appear hereinafter.

The invention consists in the combinations and arrangements of parts hereinafter described and 10 claimed.

The invention will be best understood by reference to the accompanying drawing forming a part of this specification, and in which

Fig. 1 is a face view of a beater paddle embodying the invention;

Fig. 2 an edge view of the same; and

Fig. 3 a transverse section taken substantially on line 3—3 of Fig. 2.

The embodiment of the invention illustrated in 20 the drawing comprises the usual flexible rectangular body 10 made of rubber reinforced by canvas or the like. The body 10 is provided at one end with a transverse slit 11 and with suitable bolt holes for the passage of bolts 12 by means of 25 which said body may be secured to the usual beater paddle mounts or arms of the usual spider wheel employed in such apparatus for scraping the hair from hogs in packing plants. A cup washer 12' is arranged as shown under the head 30 of each of the bolts 12 and the arrangement shown permits of some little sliding movement between the sections of the body 10 on opposite sides of the slit 11.

At its other end the body 10 is provided with the 35 usual scraper blades or clips 13 secured thereto by means of rivets 14.

In use, a plurality of paddles or scraper members are secured to the spider wheel by means of the bolts 12 and so arranged thereon as to 40 cause the scraper blade 13 to project in convenient positions to facilitate the application of the hog bodies thereto, thereby scraping or removing the hair from the hog bodies in the usual way.

45 By providing the transverse slit 11 in the secured end of the body 10 and the cup washers 12', as shown, sufficient sliding motion between the adjacent body parts and increased flexibility is obtained so that the necessary and essential bending or flexing of the paddle during operation is extended and distributed over the entire portion

of the paddle between the blades 13 and the securing rivets, thus preventing concentration of such bending at a point immediately beyond the innermost blade 13, as is usual in such paddles. It has been found that this concentration of bending at the point indicated causes relatively earlier deterioration and destruction of the paddle and that this distribution of the flexing caused by the increase of flexibility resulting from the transverse slit 11 prevents this concentration and 10 consequent injury to the paddle, whereby the useful "life" of the paddle is greatly prolonged.

While I have illustrated and described the preferred form of construction for carrying my invention into effect, this is capable of variation 15 and modification without departing from the spirit of the invention. I therefore do not wish to be limited to the precise details disclosed but desire to avail myself of such variations and modifications as fall within the scope of the appended 20 claims.

I claim:

1. A device of the class described comprising a flexible body transversely split at one end to increase its flexibility; and scraper members secured 25 to the other end of said body.

2. A device of the class described comprising a flexible body of reinforced rubber transversely split at one end to increase its flexibility and there provided with rivet holes for securing the same 30 to a traveling member; and scraper members secured to and projecting from the face of the other end of said body.

3. A device of the class described comprising a flexible body having means at one end for securing it in operative position, there being a transverse slit extending inwardly from said end to a point well beyond said securing means; and scraper members secured to the other end of said body.

4. A device of the class described comprising a flexible body having securing holes at one end for securing it in operative position, there being a transverse slit extending inwardly from said end to a point well beyond said holes; cup shaped 45 washers positioned around said holes; securing elements passing through said washers and holes; and scraper members secured to the other end of said body.
